PLATE HOLDER FOR INTAGLIO PRINTING MACHINES

Robert W. Bender, Kansas City, Mo., assignor to
Inter-Collegiate Press, Kansas City, Mo., a corporation of Missouri

Application June 15, 1936, Serial No. 85,339

6 Claims. (Cl. 101—378)

This invention relates to intaglio printing machines of the type wherein an arcuate printing plate is employed, and the primary object is the provision of an unique holder for the plate which has as a part thereof, means for removably securing the plate in place, positive guide means for the plate, and structure whereby the entire arrangement, including the plate, might be mounted upon a rotatable cylinder for adjustment longitudinally thereof.

A still further object of the invention is to provide a specially formed printing plate for intaglio printing machines, which plate is formed with an offset portion adjacent one end thereof for the purpose of engaging a coacting element on the aforesaid plate holder and to the end that the printing surface may be positively freed of excess ink or the like during work so that the plate will not produce unsatisfactory results.

A yet further aim of the present invention is the provision of a novel method of forming a plate for intaglio printing machines, which method includes the steps of engraving one side of a flat planar plate and, thereafter, arching said plate so that the same might be secured upon a concave surface and the work produced therefrom without experiencing the effects of distorted engraving which might occur if the engraving were produced upon an initially arched plate.

With the foregoing general objects in view with respect to the plate, holder therefor, and the method of producing said plate, the embodiment of the invention exemplified in the accompanying drawing will be fully described. In said drawing:

Figure 1 is a side elevation of a plate holder for intaglio printing machines embodying the invention and in operative position on the cylinder of the machine.

Fig. 2 is a top plan view of the same.

Fig. 3 is an elevation of the other side of the plate holder shown in Fig. 1.

Fig. 4 is a cross sectional view through the plate holder, with cylinder in elevation, taken on line IV—IV of Fig. 1.

Fig. 5 is an edge elevation of the formed plate per se, and,

Fig. 6 is a cross sectional view through the plate holder alone.

The plate and plate holder forming the subject matter of this particular invention is especially adaptable for use in engraving machines such as shown and described in my co-pending application Serial Number 2,700, filed

January 21, 1935, and this application is a continuation in part of said application, which relates to intaglio printing machines.

The rotatable cylinder 8 upon which is mounted one or more of the specially formed printing plates, is a part of the printing machine, and the plate holder embodying the invention is mounted upon said cylinder 8 for longitudinal movement therealong. The plate holder per se comprises a two-part collar, one of which parts 10 is provided with radially extending ears 12, through which is formed openings 14 for the reception of bolts or similar securing means 16. The other part 18 of the split collar has coacting, radially extending portions provided with tapped openings 20 in axial alignment with openings 14 so that said bolts 16 might be drawn tight when the collar is secured in the desired position on cylinder 8. A key 22 rests in key-way 24 in part 18 and coacting key-way 26 in cylinder 8 so that movement of the two-part collar about cylinder 8 is precluded.

Part 18 has a radially extending fin 28, the outer face 30 of which is arcuate and presents a convex surface concentric to the axis of rotation of cylinder 8. Fin 28 has as a part thereof, a shoulder 32, against which rests the end of printing plate 34. In the instance illustrated, fin 28 is extensive enough to accommodate two plates 34 and it is obvious that this fin might be increased in size so as to support at least one other plate. Shoulders 32 extend inwardly below face 30, and plates 34 are arranged on face 30 in end-to-end relation, with the ends thereof in abutment with shoulders 32. The other ends 35 of plates 34 extend over a recess 36 provided in fin 28, and after the plates have been mounted, the said other ends might be bent slightly inwardly, as shown in Fig. 1.

Each of plates 34 has an offset 38 created thereon adjacent one end, and in practice, it is this end of plate 34 that is considered to be the "guide end". This offset portion 38 curves inwardly out of the normal plane of the major portion of plate 34 so that shoulder 32 might be engaged, and further so that any irregularities at the end of plate 34 will not be effective in catching and transferring ink to the stock. Turning the opposite end of plate 34 inwardly as indicated in Fig. 1 so that it drops slightly into recess 36 likewise is an advantage, especially since the printing surface 40 of the plate must be wiped clean before the plate may be used efficiently. This guide end of plate 34 is used when following the method of producing an engraved

printing plate, and because of such employment, little difficulty is encountered when setting the printing machine in operation.

Each plate 34 is secured in place on fin 28 by 5 opposed clamps 42 and 44, the former being retained in place by bolts 46 that extend through clamp 42 and into tapped openings 48 drilled into fin 28. Clamp 44 is specially made and a single adjusting bolt 50 secures the same in place. 10 Bolt 50 is in threaded engagement with a tapped hole 52 provided in fin 28 and in order that clamp 44 might move away from the edge of plate 34 when bolt 50 is loosened, a spring 54 is employed and combined with the parts as illustrated in Fig. 15 4. Spring 54 is seated in a socket 56 and bears against the inner face of clamp 44 at a point adjacent to bolt 50. A laterally extending flange 58 is integral with clamp 44 along the inner face thereof and at one of its arcuate edges, and an 20 inturned, sharpened flange 60 is formed on the same surface of clamp 44 along the other arcuate edge thereof. Bolt 50 is between flanges 58 and 60 and when the bolt is tightened, spring 54 is compressed and sharpened flange 60 is drawn 25 tightly into engagement with the longitudinal edge of plate 34. The inner face of flange 58 serves as a fulcrum point and the remaining portion of clamp 44 is spaced from the adjoining face of fin 28. Under normal conditions, clamp 30 42 need not be moved when a printing plate is adjusted or replaced.

Any number of plate holders of the nature just detailed might be mounted upon cylinder 8 and, obviously, each will be independently movable 35 longitudinally along cylinder 8 so that the space between the several holders employed may be increased or decreased, as desired. A plate holder of the character specified presents means whereby a large number of calling cards, as an 40 example, may be printed at the same time and on large sheets of stock in "gang" arrangement.

Plate 34 should be formed in a particular manner and the engraving 62 of one face of plate 34 should be done before plate 34 is arched. Heretofore engraving of arched plates to produce intaglio printing has presented its difficulties because of the failure of the engraver to bring into consideration the curvature of the plate. When producing an engraved plate for use in my intaglio printing machine, the same should be engraved while it is flat and subsequently arched and provided with an offset portion 38 through novel means forming the subject matter of my application filed on even date herewith. When 55 engraving 62 is done, the end of plate 34 which is later offset with portion 38 should form the end from which to gauge or place the line passing through the center of engraving 62. When that center line is established and engraving 62 im- 60 printed on plate 34 so that it balances with respect to said line, the placement of plate 34 in the holder with that offset end in engagement with shoulder 32 will always present to the operator something like an accurate first impression. 65 Where several holders are mounted upon cylinder 8, key 22 maintains them all in alignment, and since each holder is alike, and further since offset portions 38 and shoulders 32 are always brought together, the aforesaid center line of 70 engraving 62 on every plate 34 should normally be upon a common straight line extending across the large sheet of stock being printed.

Advantages set forth in the foregoing specification will be obtained when using a plate holder 75 and plate constructed in accordance with this in-

vention, and while one preferred embodiment has been illustrated and described, it is obvious that changes might be made without departing from the spirit of the invention or scope of the appended claims.

Having thus described the invention, what is claimed as new and desired to be secured by Letters Patent is:

1. In an intaglio printing machine, a cylinder; a pair of arched plates each having a printing surface thereon; a fin mounting the plates in spaced-apart, end-to-end relation on the cylinder in spaced relation thereto; clamps on the said fin for each plate respectively for removably securing the same in operative position; and guide ele- 15 ments on the fin for said plates, said guide elements engaging the remote ends of said plates, said clamps engaging the plates along the arcuate longitudinal edges thereof.

2. In an intaglio printing machine, a cylinder; 20 a pair of plates each having a printing surface thereon; a fin mounting the plates in spaced-apart, end-to-end relation on the cylinder in spaced relation thereto; clamps on the said fin for each plate respectively for removably securing 25 the same in operative position and guide shoulders formed on the fin for said plates extending below the normal plate-supporting surface thereof, said plates each having an arcuate offset portion at one end thereof for extending below the 30 said normal surface to permit the ends at said offset portions to engage said shoulders.

3. In an intaglio printing machine, a cylinder; an arched plate, having a printing surface thereon; and means for mounting the plate on the cyl- 35 inder in spaced relation thereto comprising a two-part collar, a radially extending fin integral with one part of the collar having an arcuate plate- supporting surface, and clamping jaws on each side of the said fin for engaging the longitudinal 40 edges of said plate.

4. In an intaglio printing machine, a cylinder; an arched plate, having a printing surface thereon; and means for mounting the plate on the cylinder in spaced relation thereto comprising 45 a two-part collar, a radially extending fin integral with one part of the collar having an arcuate plate- supporting surface, and clamping jaws on each side of the said fin for engaging the longitudinal 50 edges of said plate, said fin having a guide element formed thereon for engaging one end of the printing plate.

5. In an intaglio printing machine, a cylinder; an arched plate, having a printing surface thereon; and means for mounting the plate on the cyl- 55 inder in spaced relation thereto comprising a two-part collar, a radially extending fin integral with one part of the collar having an arcuate plate- supporting surface, and clamping jaws on each side of the said fin for engaging the longitudinal 60 edges of said plate, said fin having a guide element thereon for engaging one end of the printing plate and a recess provided therein for receiving a portion of the printing plate at the other end thereof.

6. In an intaglio printing machine, a cylinder; 65 an arched plate having a printing surface thereon; and means for mounting the plate on the cylinder in spaced relation thereto, comprising a collar fitted onto the cylinder, a radially extending, relatively narrow segmental fin integral with the collar having a pair of flat sides in planes at right angles to the axis of the cylinder, and clamping jaws on the said flat sides for engaging the arched longitudinal edges of said plate.
